CONTAINER CLOSURE OR THE LIKE

Peter P. Stevens, Jr., P.O. Box 95,
Point Reyes, Calif. 94956

Filed Mar. 21, 1973, Ser. No. 343,291

Term of patent 14 years

Int. Cl. D9—07

U.S. Cl. D9—285

Fig. 3

Fig. 5

Fig. 2

Fig. 4

Fig. 1

FIG. 1 is a perspective view of a container closure or the like showing my new design;

FIG. 2 is an elevational view thereof;

FIG. 3 is a top plan view;

FIG. 4 is a horizontal sectional view taken along line 4—4 of FIG. 2; and

FIG. 5 is a horizontal sectional view taken along line 5—5 of FIG. 2.

I claim:

The ornamental design for a container closure or the like, substantially as shown and described.
